Henry G. Irmiger
INVENTOR
by Victor J. Evans

ATTORNEY

UNITED STATES PATENT OFFICE.

HENRY G. IRMIGER, OF CHICAGO, ILLINOIS.

WINDOW ATTACHMENT.

Application filed June 4, 1926, Serial No. 113,748. Renewed June 11, 1927.

This invention relates to certain novel improvements in window attachments and more particularly to a window scaffold adapted for connection in supporting relation with a window construction on the exterior side thereof and has for its principal object the provision of an improved construction of this character which will be highly efficient in use and economical in manufacture.

The present invention contemplates a novel combination and arrangement of parts for detachably connecting the platform of the scaffold in position contiguous to the window sill of the window construction whereby the platform will be supported in such a manner as to permit one, with safety, to step upon the platform in position exterior of the window construction. In accomplishing this, manifestly, the platform can be utilized as an outside ice-box or for the purpose of supporting flowers and other like objects exterior of the window construction upon the platform.

It is an object of the invention to provide a device of this character to accomplish the above purposes and whereby the device will be extremely light thereby enabling the same to be attached to or detached from the window construction.

A further object resulting from the invention is the provision for attaching the platform in supporting position whereby the platform can be used in connection with windows varying in width.

Other objects will appear hereinafter.

The invention consists in the combination and arrangement of parts to be hereinafter described and claimed.

The invention will be best understood by reference to the accompanying drawings illustrating the preferred form of my invention and in which:

Fig. 1 is a perspective view showing the invention in applied position.

Fig. 2 is a sectional detail view taken substantially on line 2-2 of Fig. 1.

Fig. 3 is a sectional detail view taken substantially on line 3-3 of Fig. 2.

Fig. 4 is a top plan view of the invention illustrating the same in applied position.

To better illustrate the application of the invention I have illustrated in the drawings, Fig. 4, a window construction 10 which includes the usual window sash 11 mounted for vertical movement in guideways 12 de-

fined in the side plates 13 of the window construction 10. This window construction defines the usual sill 14 and sub-sill 15.

The preferred form of construction embodying the invention comprises a lattice-like constructed platform 16 formed of flat light metallic strips 17 and 17' secured together in lattice-like arrangement through the medium of rivets 18. The outer end portions of the strips 17 are bent substantially at right angles as at 19, with respect to the main bodies of this strip. The opposite end portions of the strip 17' are likewise bent substantially at right angles with respect to the main bodies thereof as at 20 and to these end portions 19 and 20 is secured through the medium of rivets 21 a binding strip 22 formed of light metal. This binding strip 22, together with the strips 17 and 17', defines a basket-like shaped platform herein indicated at 16. The inner end portions 23 of the end strips 24 of the strips 17, as well as the intermediate strip 24' of the strips indicated at 17 are bent downwardly to form abutment flanges 26 adapted for bearing relation with respect to the face 27 of the sill 14. The remaining strips 17 have their inner end portions 28 in alignment with the lengths of these strips and are adapted for bearing relation upon the top 29 of the sill 14.

The above construction concludes the preferred form of construction of the platform and I will now proceed to describe briefly the means for attaching the platform 16 to the window construction 10.

The means for attaching the platform 16 in supporting relation with respect to the window construction 10 includes connecting bars 30 substantially angular in cross section as best illustrated in Fig. 4 of the drawings. These connecting bars 30 are adapted when in operative position to have their inner flanges 31 disposed in hooked relation with the outer guiding elements 32 of the upper window sash (now shown), of the window construction 10. To the other flanges 33 of these connecting bars are pivotally connected adjacent the upper ends 34 thereof, link members 35. The outer end portions of these link members 35 are pivotally connected to cooperating link members 36 as at 37. These cooperating link members 36 have their end portions 38 bent to define hooks 39 which are adapted for hooked engagement with the forward face 40 of the

binding strip 22 between certain of the strips 17.

The connecting bars 30 are forced into bearing relation with the guiding elements 32 through the medium of link members 41 and 42 having their outer corresponding end portions 43 pivotally connected to the opposite ends of the connecting bars 30 through the medium of pintles 44 carrying friction rollers 45 for rolling engagement with respect to the faces 46 of the guiding grooves 12. These pintles 44 connect these end portions of the link members 41 and 42 to the flange 31 of the connecting bars 30. The inner corresponding end portions 47 of these link members 41 and 42 are pivotally connected together through the medium of pintles 48 to which one end portion 49 of presser bars 50 are connected as best shown in Fig. 3. These presser bars, as best illustrated in Fig. 3, define inwardly inclined notches 51 which are adapted individually for the reception of a connecting pin 52 which detachably connects the presser bars 50 together for the purpose of holding the connecting bars 30 in bearing relation with the window construction 10 with the flanges 31 thereof disposed in hooked relation with the guiding elements 32.

These connecting bars 30 are forced into bearing relation with the window construction through the medium of a jack 53 which acts upon the presser bars 50 to urge the link members 41 and 42 to act upon the connecting bars 30 to force these bars into said bearing relation. This jack 53 includes a base 54 adapted for supporting position upon the top 29 of the sill 14 and defines a threaded socket 54' as best illustrated in Fig. 2 of the drawings. Threaded in this socket 54 is a lifting screw 55 which has swiveled connection as at 55', to a substantially U-shaped head 56 supporting the connecting pin 52.

In applying the invention to the window construction the connecting bars 30 are mounted in position with the flanges 31 thereof disposed to the rear of and in hooked relation with the guiding elements 32. The jack 53 is now manipulated through the medium of the handle 53' to force the lifting screw into position to cause the connecting pin to move the presser bars 50 in an upward direction about the pintles 58 so as to urge the connecting links 41 and 42 to act upon the connecting bars 30 and force these connecting bars into bearing relation with respect to the window construction in position for supporting the platform 16 exteriorly of the window construction.

After this has been accomplished the platform 16 is placed in position with the end portions 28 of the strips 17 resting upon the top face 29 of the sill 14 and with the flanges 26 in bearing relation with the face 27 of this sill.

After the platform 16 is disposed in the

position above mentioned the link members 36 are pivoted in a direction to dispose the hooks 38 thereof in hooked relation with the face 40 of the binding strip 22 between certain of the strips 17.

From the description herein it is manifest that the attaching means can be adjusted to various window sizes as it will be noted in adjusting the connecting bars the hooks 38 can be disposed in hooked relation with the face 40 of the binding strip 22 between any of the strips 17 according to the position of the connecting bars 30.

From the above description the manner in which the invention is disassembled is self explanatory.

While I have illustrated and described the preferred form of construction for carrying my invention into effect, this is capable of variations and modification without departing from the spirit of the invention. I, therefore, do not wish to be limited to the precise details of construction set forth, but desire to avail myself of such variations and modifications as come within the scope of the appended claims.

The invention having been set forth, what I claim as new and useful is:

1. A window attachment including a platform, connecting members extending upwardly from certain corresponding corners of the platform and adapted for hooked engagement with certain elements of a window construction, and link members extending from the upper end portions of the connecting members and defining hooks at their lower end portions adapted for hooked engagement with certain portions of the platform, said platform having portions disposed in bearing relation with the outer face of the sill of the window construction.

2. A window attachment including a platform having inner end portions adapted to be disposed upon the top face of a window sill of a window construction and defining other portions disposed in bearing relation with the outer face of the sill, of connecting members adapted for hooked engagement with certain elements of the window construction, a detachable connection between the connecting members and the platform, and means for forcing the connecting members into bearing relation with the window construction.

3. A window scaffold including connecting bars substantially angular in cross section adapted to have certain flanges thereof disposed behind and in hooked engagement with certain elements of a window construction when in operative position, means for forcing said connecting bars into bearing relation with the window construction, a platform defining inner portions adapted for position upon the top surface of the sill of the window construction and defining

other portions adapted for bearing relation against the outer face of the sill, and means providing detachable connections between the connecting bars and the platform.

5 4. A window attachment including a lattice-like constructed platform having certain strips defining the platform provided with end portions adapted to rest upon the top surface of a window sill of a window 10 construction and other portions defining angled end portions adapted for bearing relation with the outer face of the sill, connecting members substantially angular in cross section adapted to have certain flanges 15 thereof disposed to the rear of and in hooked engagement with certain guiding elements of the window construction, means for forcing the connecting members into bearing relation with the window construction, and 20 means connecting the connecting members to the platform, said means including hooks adapted for hooked engagement with certain portions of the platform.

5. The combination with a platform and 25 a window construction, of means for detachably connecting the platform to the window construction, said means including connecting members adapted to bear against certain elements of the window construction, 30 means providing connections between the connecting members and the platform, link members having corresponding end portions pivotally connected together and opposite corresponding end portions connected to the 35 connecting members adjacent the opposite end portions thereof, presser bars having end portions connected to said first mentioned corresponding end portions of the link members, a connecting pin for detachably 40 connecting the opposite end portions of the presser bars together, and a screw jack operable upon the connecting pin for pivoting the presser bars in a direction to urge the 45 link members to act upon the connecting members to force said connecting members

into bearing relation with the window construction.

6. The combination with a platform and a window construction, of means for detachably connecting the platform to the window 50 construction, said means including connecting members adapted to bear against certain elements of the window construction, means providing connections between the connecting members and the platform, said 55 means including link members defining hooked end portions adapted for hooked engagement with certain portions of the platform, link members having corresponding end portions pivotally connected together 60 and opposite corresponding end portions connected to the connecting members adjacent the opposite end portions thereof, presser bars having end portions connected to said first mentioned corresponding end portions 65 of the link members, a connecting pin for detachably connecting the opposite end portions of the presser bars together, and a screw jack operable upon the connecting pin for pivoting the presser bars in a direction 70 to urge the link members to act upon the connecting members to force said connecting members into bearing relation with the window construction.

7. The combination with a window construction, of a basket-like constructed platform defining a binding strip and strips having end portions adapted to be disposed upon the top surface of the sill of a window construction and having other strips defining angled end portions disposed in bearing relation with the outer face of the sill, and means for detachably connecting the platform to the window construction, said means including members having hook shaped end 80 portions adapted for detachable hooked engagement with the binding strip between certain of said other strips.

In testimony whereof I affix my signature.
HENRY G. IRMIGER.
